UNITED STATES PATENT OFFICE.

SAMUEL E. HYNDMAN, OF CINCINNATI, OHIO.

FENCE-POST.

SPECIFICATION forming part of Letters Patent No. 289,349, dated November 27, 1883.

Application filed August 11, 1882. Renewed June 23, 1883. (No model.)

To all whom it may concern:

Be it known that I, SAMUEL E. HYNDMAN, of Cincinnati, in the county of Hamilton and State of Ohio, have invented a new and useful

5 Improvement in Fence-Posts, which improvement is fully set forth in the following specification and accompanying drawings, in which—

Figure 1 is a perspective view of my improved post with the wires attached thereto. 10 Fig. 2 is a perspective elevation of part of post; Fig. 3, perspective view of portion of post, showing modified means of attaching the wires thereto; and Fig. 4 is a perspective view of the post-supporting disk.

15 The object of this invention is to make a durable fire-proof fence-post constructed of metal. It consists of a single strip of sheet metal cut into the proper length for a fence-post, and of sufficient width that it may be

20 bent to form a triangular body, having a flange at the united or joined edges, provided with a series of holes or perforations to receive the fence-wires, in combination with a metallic disk of any suitable size, with an aperture in 25 the center of the shape and size of the post, which slips over the post. This is to be secured to the post at any suitable point, or it may be placed on the post without being permanently fastened thereto.

30 In the accompanying drawings, A represents the post bent so as to form a triangular body, the two uniting edges being provided with flanges B. Through these flanges are formed holes or perforations C, to receive the 35 wires D.

E represents a metallic disk of any suitable size, but preferably about three times the diameter of the post A. Centrally is an aperture, F, of suitable size and shape to permit 40 the post A to enter the same, and thus placed the said plate operates to bind and hold the post in permanent shape. In practice it is designed to have the aperture F so that the post will fit snugly therein, so that when the 45 disk is located at any point on the post it may

not be readily moved. However, if desired, the disk may be permanently attached to the post; but this is not essential.

In putting down posts the disk is laid on the ground at the proper point, so that the 50 flange-recess G of the disks projects at right angles to the projected wires or line of the fence, and the post A placed in the aperture F and driven into the ground the proper distance. The disk will, therefore, rest on the 55 surface of the ground snugly when the post has been driven home, thus affording a support or brace for the post, which is the object of this device. The disk may be keyed in place or braced by a bolt, e, which passes close 60 above it through the edges of the post, and rests flat on its upper surface.

In Fig. 3 I show a simple and convenient manner of constructing the holes for the wires. This consists in having the flange B slotted 65 from the holes C, as shown by H, so that in attaching the wire to the post the slotted point is turned to one side, permitting the wire to be inserted when the point is again turned back to its original position. 70

I am aware that it is not new to form a fence-post in triangular shape by folding a strip of sheet metal longitudinally; also, that it is not new to use a disk on a metal fence-post. 75

Having described my invention, what I claim is—

A fence-post composed of a single piece of sheet metal triangular in shape, and having a flange at its united edges, combined with the 80 disk E, having aperture F, and flange-recess G, substantially as shown and described.

In testimony that I claim the foregoing I have hereunto set my hand, this 3d day of August, 1882, in the presence of witnesses.

SAMUEL E. HYNDMAN.
